UNITED STATES PATENT OFFICE.

CHRISTIAN WELLER, OF ATLANTIC CITY, NEW JERSEY.

METHOD OF LAYING AND COVERING PIPES AND THE LIKE.

Application filed July 14, 1927. Serial No. 205,626.

My invention relates to a new and useful improvement in the method of laying and covering pipes and the like, and has for its object to provide for the formation of 5 trenches within cement, concrete or similar road beds and for covering such pipes or the like with removable sectional blocks.

A further object of my invention is to provide closure blocks of the same or 10 analogous material as the road bed, and of such shape as to be jambed into the trench and there sealed to complete the road bed.

A still further object of my invention is to provide for protecting the pipes in such 15 trenches from cold and also for the ready removal of the closure blocks for gaining access to said pipes.

With these ends in view, this invention consists in the details of construction and 20 combination of elements hereinafter set forth and specifically designated by the claims.

In order that those skilled in the art to which this invention appertains may understand 25 how to make and use the same, I will describe its construction in detail, referring by numerals to the accompanying drawings forming a part of this application, in which:

Fig. 1 is a plan in perspective of a number 30 of city streets showing the method of embedding pipes and the like in trenches; in one direction the trenches being continuous while in the cross-wise direction these trenches are shown as sectional or in parquet 35 form.

Fig. 2 is an enlarged plan view of one of the closure blocks set in a road bed showing the eyes for removing it from its trench.

Fig. 3 is a section on the line 3—3 of 40 Fig. 2.

Fig. 4 is a perspective view of one of the closure blocks.

Fig. 5 is a section similar to Fig. 3 showing the trench lined with cork or similar material providing yielding surfaces for the 45 closure blocks when inserted in the trench.

In carrying out my invention as herein embodied, 50 represents the road bed constructed of well-known material such as concrete or cement, and in the construction of such road beds where they are relatively thin an increased thickness may be provided throughout certain lines as indicated at 55 for the formation of the trenches 12 of sufficient depth to properly protect the pipes or

cables 13 laid within said trenches. These trenches are preferably formed when the road bed is being laid and may be either continuous as indicated at 12^a in Fig. 1 or in sections or parquet form as indicated at 12^b 60 as may best suit the conditions for which the pipes or cables are to serve.

The trenches 12 have their side walls inclined inward from top to bottom for the proper reception of the wedge-shape closure 65 blocks 14, which blocks are preferably made of the same or substantially the same material of which the road bed is made, so that when these blocks are fitted within the trenches, as shown in Figs. 1 and 3, they will 70 be wedged therein in such manner as to sustain the weight of traffic over the road bed without bringing undue pressure to bear upon the pipes or cables; and in practice, the walls of the trenches have applied thereto 75 asphaltum material in a hot or liquid state, so that when the closure blocks are wedged within these trnches, a water-tight union is formed between the road bed and the closure blocks, leaving the surface of the road 80 bed in a smooth and unbroken condition.

By this method, not only are the pipes or cable within the trenches protected against the elements and the road bed left in a perfect condition, but access may be readily had 85 to the pipes or cables by applying sufficient heat to the road bed and blocks adjacent to the trench to sufficiently soften the asphaltum to permit the removal of one or more of the blocks. To facilitate the removal of 90 these blocks, two eyes 15 are set in each block so that lifting hooks may be inserted in said eyes for drawing the blocks upward; the eyes being below the surface of the blocks by being set in the depressions 16 and these de- 95 pressions in practice will be filled with asphaltum in order to complete the surface of the block and give the normal appearance to the road bed, but the asphaltum in these depressions may be sufficiently softened by 100 the application of heat to enable the eyes to be engaged by suitable lifting hooks.

Where the trenches are formed in the road beds in continuous lengths, the closure blocks are set therein end against end and sealed 105 in the same manner utilized in sealing the side surfaces of the blocks as just described.

Where the trenches are made in sections or in parquet form, each length of the trench has provided therefor a closure block which 110

snugly fits therein and all of the abutting surfaces of such blocks are sealed to the corresponding surfaces of the road bed, the sealing material being indicated at 17 in Figs. 5 2 and 3.

Where it is found desirable to line the trenches for the special protection of the pipes or cables laid therein, I utilize layers of cork or similar material 18 as shown in Fig. 5, and when such lining is used, not only are the pipes or cables protected against the elements, but a cushioning effect is given to the blocks.

Heretofore, serious disadvantages have been encountered in the laying of pipes, cables and the like in road beds, usually requiring expensive conduits to which easy access throughout the length of the pipes or cables cannot be had, whereas by my invention, these disadvantages are entirely overcome and a cheap and simple method is provided for laying and covering such pipes or cables, and yet giving ready access to the same throughout their lengths and without in any way injuring or marring the appearance of the surface of the road bed. This is of great importance, especially in road beds extending throughout country districts, and also for city streets.

In practice, I have found it desirable to form a channel-way 19 in the bottom surface of each of the closure blocks for partially enclosing the pipe or cable laid within the trench.

When pipes and the like have been laid by my improved system and it becomes necessary or desirable to gain access thereto for removal, renewal or repair, such access is readily had at any point throughout the length of the trench by simply removing the required number of closure blocks in the manner before described, and when the repair work has been accomplished, the blocks may be again relaid leaving the road bed in perfect condition; and this feature is of great importance in connection with crowded city streets.

Of course I do not wish to be limited to the exact details of construction as herein shown, as these may be varied within the limits of the appended claims without departing from the spirit of my invention.

Having thus fully described my invention, what I claim as new and useful is:

1. The combination of a trench formed in a road bed, and a series of blocks for closing said trench and forming a continuation of the surface of the road bed, said

blocks being hermetically sealed in said trench.

2. The herein described combination of a trench formed in a road bed, said trench having its walls converging downward; a series of blocks corresponding in cross-section to the cross-section shape of the trench so as to be wedged into said trench, the said blocks being adapted to be hermetically sealed within the trench; and means carried by the blocks to be engaged by an elevating medium for lifting the blocks out of the trench.

3. In combination with a trench formed in a road bed having its walls converging toward the bottom thereof; a pipe laid in the bottom of said trench; a series of V-shaped blocks adapted to be wedged into the trench, each of said blocks having a channel-way in the lower surface thereof; and means carried by the blocks to be engaged by an elevating medium for lifting said blocks from the trench.

4. In combination with a trench adapted to receive pipes, cables and the like, layers of cork, covering the side walls of said trench; and V-shaped blocks adapted to be wedged into said trench against said cork lining.

5. In combination with a road bed; a sectional trench formed in the road bed and having a semi-circular seat in the bottom thereof for positioning pipes and the like, said sections having V-shaped side walls; V-shaped blocks adapted to snugly fit within said sections, said blocks having semi-circular channel-ways formed in the lower surface thereof for seating upon said pipes and the like; two eyes, each set in a depression formed in the block whereby the latter may be readily removed.

6. In a combined paving conduit system, a road bed having trenches formed therein, said trenches having V-shaped side walls and semi-circular channel ways in the bottom thereof for positioning pipes and the like within the trenches, blocks for closing said trenches, said blocks having V-shaped side walls and semi-circular channel ways in the bottom surfaces thereof, said blocks also having depressions in the upper surface thereof, and links set within the blocks so that their upper ends project into said depressions and form lifting eyes.

In testimony whereof, I have hereunto affixed my signature.

CHRISTIAN WELLER.
